TRIGGERED OSCILLATOR

Paul B. King, Jr., Cambridge, Mass., assignor to
 Raytheon Manufacturing Company, Newton,
 Mass., a corporation of Delaware

Application March 10, 1938, Serial No. 195,111

7 Claims. (Cl. 250—36)

This invention relates to an oscillator which it is desired to start and stop periodically.

One of the objects of this invention is to devise an oscillator which will start generating alternating currents upon a simple impulse being imparted thereto.

Another object is to devise such an oscillator which if momentarily stopped will not start again until the impulse mentioned above is received.

10 A further object is to devise simple means for stopping such an oscillator.

An additional object is to devise such a system by incorporating therein a gas-filled cath-anode discharge tube.

15 The foregoing and other objects of my invention will be best understood from the following description of exemplifications thereof, reference being had to the accompanying drawing, wherein:

20 Fig. 1 is a diagram illustrating one embodiment of my novel oscillator;

Fig. 2 is a diagrammatic representation of a detail of the system shown in Fig. 1 as applied to an automatic telegraph system;

25 Fig. 3 is another diagram illustrating another embodiment of my invention; and

Fig. 4 is an additional diagram illustrating a further embodiment of my invention.

In the application of Wilcox P. Overbeck for 30 an improvement in Cathanode tube oscillators, Serial No. 195,071, filed March 10, 1938, there is described and claimed an oscillating circuit using a so-called cathanode tube which is a gas-filled discharge tube of the type described and claimed 35 in the patents to Charles G. Smith, No. 1,962,158, and James D. Le Van, No. 1,962,159. I have discovered that an oscillator of the type described in said Overbeck application can be positively started and stopped by the utilization of simple 40 switching means.

In Fig. 1, which illustrates an oscillator of the general type described and claimed in said Overbeck application, there is shown a cathanode tube 1. This cathanode tube is filled with an ionizable 45 gas or vapor at sufficient pressure so that ionization of said filling may be produced upon the passage of a discharge therethrough. The tube contains a cathode 2, preferably of the indirectly-heated thermionic type, having a heater element 3, whereby it may be heated to temperature of 50 thermionic emission. There is also provided a perforated electrode 4 spaced from the cathode 2 a distance substantially greater than the mean free path of the molecules of the medium within 55 the tube, so that a gaseous discharge may be

produced between the cathode 2 and the electrode 4 which results in the formation of a large number of positive ions and electrons in the intervening space. Electrons from said intervening space pass through the openings in the electrode 4, which then acts as a virtual cathode for the space behind it. It is for this reason that the electrode 4 is termed a cathanode. Spaced from the cathanode 4 by a distance of the order of magnitude of the mean free path of the molecules 10 in the gas is the anode 6. Between the cathanode 4 and the anode 6 is interposed the control electrode 5. Due to the spacing between the anode 6 and the cathanode 4, the discharge in the intervening space is under complete control by the 15 voltage impressed upon the control electrode 5. As described in said patents to Smith and Le Van, it is desirable that the electrons emitted from the cathode 2 be confined to the space between the cathode and the cathanode so that such electrons cannot pass into the region controlled by the electrode 5, except through the openings in the cathanode.

In order to supply the tube with power, a conductor 7 connects the cathode 2 to the negative 25 terminal of a suitable source of direct current. A conductor 8 connects the anode 6 to the upper end of an induction coil 9 having a tap 10 adjacent the opposite end thereof. A conductor 11 connects the tap 10 to the positive terminal of 30 said source of direct current. Across the coil 9 is placed a condenser 12 which forms with said coil a tank circuit in which oscillating currents may be set up. In order to supply energy to the cathode-cathanode space during the production 35 of oscillations in the tank circuit, as more fully described and claimed in said Overbeck application, a conductor 13 extends from the lower end of the coil 9 through the condenser 14 to the cathanode 4. The cathanode 4 is likewise connected back to the cathode 2 by means of a leakage resistance 15. In order to supply the proper 40 voltage to the control electrode 5 so that oscillations may be produced, said control electrode 5 is connected to the conductor 13 through a condenser 16. Said control electrode is also connected back to the cathode through a leakage 45 resistance 17. When such a system is set in operation, oscillations are produced in the tank circuit. These oscillations may be taken off by 50 means of a coil 18 coupled to the coil 9. The oscillations so taken may be fed into a suitable output device 19.

If such a system as I have described above is connected to the source of direct current and 55

oscillations are not initiated therein, the circuit will remain in such a condition of inactivity until a starting impulse is imparted to the system. In order to supply this starting impulse, a conductor 20 connects the cathanode 4 to the switch arm 21 which is adapted to contact with the stationary switch contact 22. A current-limiting resistance 23 is connected between the contact 22 and the conductor 11 which extends to the positive terminal of the direct current source. If the switch 21 is moved so as to close the contact 22, the voltage of the source will be impressed between the cathode and the cathanode through the current-limiting resistance 23. This will produce a flow of current between the cathode and the cathanode which will generate positive ions and electrons in the intervening space, and thereupon the oscillating circuit will start operating to produce alternating currents flowing in the tank circuit, and thus into the output device 19. Such a closure of the contact 22 need be only momentary, inasmuch as when this contact is opened, the system will continue to generate oscillations until some steps are taken to stop such oscillations.

In order to stop oscillations in the system described above, there is provided a stationary contact 24 also adapted to cooperate with the switch arm 21. A conductor 25 connects the contact 24 directly with the conductor 7 which leads to the cathode 2. When the switch arm 21 is moved over into contact with the contact 24, the discharge space between the cathode and the cathanode is short-circuited through the conductor 20, the switch arm 21, the contact 24, and the conductors 25 and 7. This short circuit removes the possibility of voltages existing between the cathode and the cathanode, and thus stops the flow of current between these electrodes, and also eliminates the creation of ionization in said space. Therefore, when the switch 21 is moved into contact with the contact 24, all oscillations in the tank circuit are stopped, and thus the alternating current ceases to flow in the output device 19.

From the above description we see that if the switch arm 21 is moved into contact with either the contact 22 or the contact 24, oscillations will be started or stopped in the system, and each condition will persist until the switch arm 21 is moved deliberately into contact with the opposite contact so as to change the condition of operation. It will be seen, therefore, that I have devised a simple trigger arrangement for stopping and starting oscillations. Such a simple triggered system is useful in many applications, particularly in the art of telegraphy and other associated signalling arts.

Fig. 2 shows a detail of the system illustrated in Fig. 1 as applied to the art of telegraphy. In Fig. 2, where the conductors or elements are identical with those in Fig. 1, the same reference numerals are applied thereto. In Fig. 2 there is shown a perforated tape 26 of the type which is used at the present time in automatic telegraph keying systems. This tape is provided with two lines of perforations 27 running along the length of the tape. The distance between adjacent perforations in the opposite lines is designed to represent either a dot or a dash. Thus, for example, two of the openings in Fig. 2 are shown as being separated by a short distance B, which represents a dot, while two other openings are represented as being separated a longer distance 75 A, which represents a dash. Below the two lines

of perforations are two contacts 28 and 29. Above the two lines of perforations are the two spring contacts 30 and 31. As the tape 26 is moved in the direction of the arrow at the left of Fig. 2, each contact above the tape will extend through an opening 27 and come into contact with the contact below the tape each time an opening passes the respective pair of contacts. As movement of the tape, however, continues, each pair of contacts is again opened until a succeeding perforation passes said pair of contacts.

In order to adapt such an arrangement to the system shown in Fig. 1, the two upper contacts 30 and 31 may be connected together by means of a conductor 32. The conductor 20 which extends to the cathanode 4 of Fig. 1 is then connected to the common conductor 32. The lower contact 28 is connected to the conductor 5 of Fig. 1 while the lower contact 29 is connected to the resistance 23 of Fig. 1. Under these conditions, when a perforation passes the contacts 29 and 31, the circuit through the resistance 23 will be closed and the system of Fig. 1 will start generating oscillations. Such oscillations will continue until a perforation passes the contacts 30 and 28, whereupon the shortcircuiting connection through the conductor 25 will be completed, stopping the oscillations of the system. Therefore, as the perforated tape is passed through the system, there will appear in the output 19 a series of pulses of oscillations. The length of each pulse will be dependent upon the distance between the starting and stopping perforations in the tape 26. Since these distances correspond to dots and dashes, the desired code signal will be created in the output device 19.

Other means than those shown in Fig. 1 may be utilized to stop the oscillations. For example, the arrangement as shown in Fig. 3 may be utilized. In this figure where the elements are identical with those of Fig. 1, the identical reference numerals are applied. In Fig. 3 the conductors 7 and 11 are supplied with direct current through a control device 33 which is energized through a pair of conductors 34 from a suitable source of direct current. The controlling device 33 is devised so that it removes the direct current voltage from the conductors 7 and 11 at any desired time. The device 33 may be, for example, a simple switch to disconnect the conductors 34 from the conductors 7 and 11. Removal of this voltage will stop the oscillations of the system, and such oscillations will not be re-initiated merely upon an ordinary re-application of the direct current voltage. Therefore, in order to re-start the system, the conductor 20 which extends from the cathanode 4 is connected to a stationary contact 35 which is paced from and adjacent a stationary contact 36. The resistance 23 is connected between this stationary contact 36 and the conductor 11. A pushbutton 37 is provided which in its closed position interconnects the contacts 35 and 36, thus completing the starting circuit to the cathanode 4. The pushbutton 37 is normally biased in its open position by means of a spring 38.

In Fig. 3 the system is set in oscillation by a momentary closure of the pushbutton 37, and is stopped from oscillating by a removal of the voltage from the conductors 7 and 11, either momentarily or for any desired longer period.

In the circuits described in Figs. 1 and 3, the condenser 14 and the leakage resistance 15 impress a negative potential on the cathanode 4 so that in order to produce a gaseous discharge in

the space between the cathode 2 and the cath-anode 4, it is necessary for the oscillating circuit to swing the cathanode through a considerable amplitude of voltage in order to make it positive, at which time the gaseous discharge is produced. If it is desired to impress upon the cath-anode a smaller voltage swing, such an arrangement as shown in Fig. 4 may be utilized. In Fig. 4 there is shown a cathanode tube 39 of the same type as described in connection with the cath-anode tube 1 of Figs. 1 and 3. This tube is filled with an ionizable gas or vapor and contains a cathode 40, a control element 41, a cathanode 42, a control electrode 43, and an anode 44. The pressure of the gas and the spacing between the various electrodes are as described in connection with Figs. 1 and 3.

In order to supply the tube with power, a conductor 45 extends from the cathode 40 to the negative terminal of a suitable source of direct current. A conductor 46 connects the anode 44 to the upper end of an induction coil 47, the other end of which is connected by a lead 48 to the positive terminal of the source of direct current. Across the coil 47 is placed a condenser 47' which forms with said coil a tank circuit in which oscillating currents may be set up. In order to produce a feed-back into the control grid 43 so as to maintain the oscillations, a coupling coil 49 is coupled to the coil 47. One end of the coil 49 is connected by means of a conductor 51 to the control electrode 43, and the other end of said coil is connected by means of a conductor 50 to the lead 45, and thus to the cathode 40. In such a circuit, when a gaseous discharge is initiated between the cathode 40 and the cathanode 42, oscillations are set up in the tank circuit consisting of the coil 47 and the condenser 47'.

In order to supply energy to the cathode-cathanode space for producing the gaseous discharge mentioned above, the following circuit arrangements are made. Between the two conductors 45 and 48 is connected a potentiometer 52. This potentiometer is provided with a tap 53 which is at a potential with respect to the cathode 40 less than that at which a gaseous discharge will be produced between the cathode 40 and the cathanode 42. In the case of a mercury vapor-filled tube, this is preferably less than about ten volts. A conductor 54 connects said tap to one end of a coil 55 coupled to the coil 47. A conductor 56 connects the opposite end of said coil 55 to the conductor 57, and thus to the cathanode 42. By this arrangement a positive bias is impressed upon the cathanode 42 which, however, is insufficient of itself to initiate the gaseous discharge. However, due to the fact that the coil 55 is coupled to the coil 47, an alternating voltage due to the oscillating currents in the tank circuit will be induced in the coil 55, and thus superimposed upon the cath-anode 42. A relatively small voltage swing in the positive direction will raise the voltage upon the cathanode 42 sufficiently to initiate the requisite gaseous discharge between the cathode 40 and the cathanode 42. Each positive swing of the voltage across the coil 55 will produce a pulse of gaseous discharge current in the cathode-cathanode space. In order that the system may work properly, the varying voltages upon the electrodes 42 and 43 should be in phase. Thus, when the cathanode 42 becomes more positive, the control electrode 43 likewise becomes more positive, and upon the passage of the gaseous

discharge, a pulse of current flows to the anode 44 and thus to the tank circuit. These pulses of current maintain the oscillations in said tank circuit.

Since an ordinary application of voltage to the conductors 45 and 48 will not initiate a gaseous discharge in the cathode-cathanode space, it is necessary to provide some positive means for starting the oscillations. For this purpose the potentiometer 52 is provided with a tap 58 which is at a higher positive potential than the tap 53. The voltage of the tap 58 is sufficient to initiate the requisite gaseous discharge between the cathode and the cathanode. The tap 58 is connected through a current-limiting resistance 59 to a switch contact 60. A switch arm 61 is provided and adapted to be brought into contact with the contact 60. The switch arm 61 is connected by means of a conductor 62 to one end of a parallel circuit consisting of an induction coil 63 and a condenser 64. The other end of said parallel circuit is connected to the conductor 57, and thus to the cathanode 42. When the switch arm 61 is brought into contact with the contact 60, the voltage of the tap 58 will be impressed upon the cathanode 42, and thus will initiate the operation of the system. The closure of the contact 60 need be only momentary inasmuch as when the operation of the system starts, oscillations will continue and all of the requisite energy for the cathode-cathanode space will be supplied by means of the circuit including the coil 55.

The coil 63 and condenser 64 are provided for the purpose of preventing surges in the output of the system. In some instances the sudden application of a positive voltage to the cath-anode 42 results in a relatively large surge of current in the cathode-cathanode space, which results in an excessive surge of current in the oscillating circuit and thus in the output of the system. In a telegraph system these surges manifest themselves in the output as key clicks. If, however, the coil 63 and condenser 64 are provided, they introduce a sufficient time lag in the circuit, applying starting voltage to the cathanode to prevent a too sudden application of said starting voltage. Of course in many instances the coil 63 and condenser 64 may be entirely omitted.

The oscillations of the circuit as shown in Fig. 4 may be stopped in various ways. For example, the arrangement as shown in Fig. 1 may be used. In this case the system in Fig. 4 is provided with a stationary contact 65 adapted to cooperate with the switch arm 61. The contact 65 is connected by means of a conductor 66 to the lead 45 and thus to the cathode 40. When the switch arm 61 is moved into contact with the contact 65, the cathode-cathanode space is short-circuited, and the production of a gaseous discharge therein is prevented. In this way the operation of the system ceases. Of course other means of stopping the production of oscillations in Fig. 4 could likewise be used.

The output of the circuit in Fig. 4, controlled as indicated above, may be fed through a coupling coil 67 to a suitable output device 68.

Of course it is to be understood that this invention is not limited to the particular details as described above, as many equivalents will suggest themselves to those skilled in the art, and the principles of this invention will find a wide application to various electrical arts. It is accordingly desired that the appended claims be

given a broad interpretation commensurate with the scope of this invention.

What is claimed is:

1. An oscillating system comprising an electrical gaseous discharge device comprising an envelope containing electrodes including a cathode, a cathanode spaced from said cathode, an anode spaced from said cathanode, a control electrode for controlling a discharge between said cathode and said anode, and a gaseous medium in said envelope at a pressure at which substantial ionization of said medium may be produced, an oscillating circuit connected between the anode and other electrode and adapted to be maintained in oscillation by said discharge device, means for impressing a voltage upon said anode for supplying energy to said system, means for feeding energy from said oscillating circuit to the cathanode for producing a gaseous discharge in the cathode-cathanode space, additional means for supplying energy to said cathanode to start a gaseous discharge in said cathode-cathanode space for initiating the production of oscillations in said oscillating circuit, and means for preventing the feeding of energy from said oscillating circuit to said cathanode for stopping said oscillations while said anode is still applied.

2. An oscillating system comprising an electrical gaseous discharge device comprising an envelope containing electrodes including a cathode, a cathanode spaced from said cathode, an anode spaced from said cathanode, a control electrode for controlling a discharge between said cathode and said anode, and a gaseous medium in said envelope at a pressure at which substantial ionization of said medium may be produced, an oscillating circuit connected between the anode and other electrode and adapted to be maintained in oscillation by said discharge device, means for impressing a voltage upon said anode for supplying energy to said system, means for feeding energy from said oscillating circuit to the cathanode for producing a gaseous discharge in the cathode-cathanode space, additional means for supplying a pulse of energy to said cathanode to start a gaseous discharge in said cathode-cathanode space for initiating the production of oscillations in said oscillating circuit, and means for preventing the feeding of energy from said oscillating circuit to said cathanode for stopping said oscillations, while said anode is still applied.

3. An oscillating system comprising an electrical gaseous discharge device comprising an envelope containing electrodes including a cathode, a cathanode spaced from said cathode, an anode spaced from said cathanode, a control electrode for controlling a discharge between said cathanode and said anode, and a gaseous medium in said envelope at a pressure at which substantial ionization of said medium may be produced, an oscillating circuit connected between the anode and other electrode and adapted to be maintained in oscillation by said discharge device, means for impressing a voltage upon said anode for supplying energy to said system, means for feeding energy from said oscillating circuit to the cathanode for producing a gaseous discharge in the cathode-cathanode space, additional means for supplying energy to said cathanode to start a gaseous discharge in said cathode-cathanode space for initiating the production of oscillations in said oscillating circuit, and means

for short-circuiting said cathode-cathanode space for stopping said oscillations.

4. An oscillating system comprising an electrical gaseous discharge device comprising an envelope containing electrodes including a cathode, a cathanode spaced from said cathode, an anode spaced from said cathanode, a control electrode for controlling a discharge between said cathanode and said anode, and a gaseous medium in said envelope at a pressure at which substantial ionization of said medium may be produced, an oscillating circuit connected between the anode and other electrode and adapted to be maintained in oscillation by said discharge device, means for impressing a voltage upon said anode for supplying energy to said system, means for feeding energy from said oscillating circuit to the cathanode for producing a gaseous discharge in the cathode-cathanode space, additional means for supplying energy to said cathanode to start a gaseous discharge in said cathode-cathanode space for initiating the production of oscillations in said oscillating circuit, and means for momentarily short-circuiting said cathode-cathanode space for stopping said oscillations.

5. A system comprising an electrical gaseous discharge device comprising an envelope containing a cathode, a cathanode spaced from said cathode, an anode spaced from said cathanode, a control electrode for controlling a discharge between said cathanode and said anode, and a gaseous medium in said envelope at a pressure at which substantial ionization of said medium may be produced, means for impressing a voltage upon said anode for supplying energy to said system, means for applying a positive bias to said cathanode of insufficient value to initiate a gaseous discharge between said cathode and cathanode, said positive bias continuing throughout the normal operation of the device, means for superimposing upon said positive bias an alternating voltage to periodically produce a gaseous discharge between said cathode and cathanode, and means for supplying a control voltage to said control electrode substantially in phase with said alternating voltage.

6. An oscillating system comprising an electrical gaseous discharge device comprising an envelope containing electrodes including a cathode, a cathanode spaced from said cathode, an anode spaced from said cathanode, a control electrode for controlling a discharge between said cathanode and said anode, and a gaseous medium in said envelope at a pressure at which substantial ionization of said medium may be produced, an oscillating circuit connected between the anode and other electrode and adapted to be maintained in oscillation by said discharge device, means for impressing a voltage upon said anode for supplying energy to said system, means for feeding energy from said oscillating circuit to the cathanode for producing a gaseous discharge in the cathode-cathanode space, a circuit for supplying energy to said cathanode to start a gaseous discharge in said cathode-cathanode space for initiating the production of oscillations in said oscillating circuit, and means interposed in said circuit having a sufficient time delay to prevent surges in the oscillating circuit upon the initial application of said supply of energy.

7. An oscillating system comprising an electrical gaseous discharge device comprising an envelope containing electrodes including a cathode, a cathanode spaced from said cathode, an anode

spaced from said cathanode, a control electrode for controlling a discharge between said cathanode and said anode, and a gaseous medium in said envelope at a pressure at which substantial ionization of said medium may be produced, an oscillating circuit connected between the anode and other electrode and adapted to be maintained in oscillation by said discharge device, means for impressing a voltage upon said anode for supplying energy to said system, means for feeding energy from said oscillating circuit to the

cathanode for producing a gaseous discharge in the cathode-cathanode space, a circuit for supplying energy to said cathanode to start a gaseous discharge in said cathode-cathanode space for initiating the production of oscillations in said oscillating circuit, and an inductance and condenser connected in parallel and interposed in said circuit to prevent surges in the oscillating circuit upon the initial application of said supply of energy.
